SLICING MACHINE

George R. Wood, Montreal, Quebec, Canada, assignor to Toledo Scale Company, Toledo, Ohio, a corporation of New Jersey

Application April 12, 1943, Serial No. 482,768

2 Claims. (Cl. 146—102)

1

This invention relates to slicing machines of the type in which a commodity to be sliced is reciprocated past an exposed edge of a rotary circular knife, a slice of commodity being severed during each stroke, and more particularly to means for deflecting such severed slices away from the rear face of the knife onto slice-receiving means or into position to be gripped by the operator.

It is an object of this invention to provide a slice deflector which is easily removable in order to expose the rear face of the rotary circular knife to facilitate cleaning.

It is another object of this invention to provide a slice deflector, the mounted position of which can be adjusted with respect to the rear face of the cutting knife to bring the edges of the deflector into close proximity thereto.

It is a further object of this invention to provide a slice deflector which is mounted on a slicing machine and held thereon by a mounting means which does not form any projection or obstruction on the external surface of the slice deflector.

More specific objects and advantages are apparent from the description, in which reference is had to the accompanying drawings illustrating a preferred form of machine embodying the invention.

In the drawings:

Fig. I is a fragmentary view, in elevation, of a "modern" style slicing machine incorporating a slice deflector embodying the invention.

Fig. II is a fragmentary view, in elevation, taken from the right side of Fig. I.

Fig. III is a fragmentary view, taken substantially from the position shown by the line III—III in Fig. II.

Fig. IV is a fragmentary detailed view, in section, taken substantially on the line IV—IV of Fig. II.

Fig. V is a fragmentary view, in perspective, of the latching means shown in Fig. IV.

Fig. VI is a view similar to Fig. I but of a different type of slicing machine incorporating a deflector embodying a modification of the invention.

Fig. VII is a fragmentary view, in elevation, taken from the right side of Fig. VI.

Fig. VIII is a fragmentary vertical sectional view, taken substantially on the line VIII—VIII of Fig. VII.

Fig. IX is a detailed view, in elevation, taken

from the left side of Fig. VIII, certain parts being broken away.

These specific drawings and the specific description that follows merely disclose and illustrate the invention and are not intended to impose limitations upon the claims.

A slicing machine, with which a deflector embodying the invention is adapted to be used, may comprise a base 10, atop which is mounted a housing 11 containing mechanism for driving a rotary circular knife 12. A gauge plate 13 serves to gauge the thickness of slices of commodity to be severed by the knife 12. A deflector 14, which, in the embodiment shown, has an exterior contour conforming to the contour of the remaining parts of the slicing machine adjacent which it is mounted, is located at the rear of the rotary circular knife 12 to deflect slices of commodity onto the upper surface of a slice-receiving platter 15 mounted below and at the rear of the gauge plate 13.

A pair of ears 16 extend horizontally rearwardly from the inner surface of the deflector 14 through two apertures 17 in a front wall 18 of the housing 11. Near the rearmost end of each of the ears 16 there is riveted a button 19 which has a shank 20 of smaller diameter than the diameter of its flat head 21. The head 21 is spaced below the ear 16 by the shank 20. An angle bracket 22 has its vertical flange bolted to the inner face of the wall 18 of the housing 11 and its horizontally-turned flange is located immediately behind the two apertures 17 in the wall 18. Two openings 23 are cut in the corner of the plate 22 immediately behind the apertures 17. Each of the openings 23 comprises a wide shallow slot 24, cut in the vertical flange of the bracket 22, and a narrow curved slot 25, cut in the horizontal flange of the bracket 22 and blending into the slot 24 at the corner of the angle.

The buttons 19 are engaged in the openings 23 by inserting their flat heads 21 through the slots 24 and engaging their shanks 20 with the narrower curved slots 25 and then sliding the entire deflector and its ears 16, with the buttons 19, forwardly toward the rear of the knife 12 to move the shanks 20 to the limits of the slots 25 as shown in Fig. IV.

The curved slots 25 of the openings 23 thus limit the movement of the deflector plate 14 toward the rear of the knife 12 and also, due to their curved shape, pull the deflector snugly into position adjacent the wall 18 of the housing 11. The position of the deflector 14, relative to the

knife 12, may be adjusted by varying the position of two bolts 26 which extend through counterbored holes 27 in the wall 18 of the housing 11 and hold the angle bracket 22 in place. By loosening the bolts 26, and shifting them in the enlarged counterbored holes 27, the position of the angle bracket 22, and thus the deflector 14, may be adjusted to make the edge of the deflector 14 parallel to the rear face of the knife 12 and also to vary the space between such edge and such face.

A lower portion 28 of the deflector 14 also serves to guard a small portion of the rotary circular knife 12 which is located below the edge of the gauge plate 13, as can be seen in Fig. III. The portion 28 of the deflector 14 cooperates with a tab 29 extending downwardly from a knife guarding means 30 located over the forward face of the knife 12. This provision of a portion of the deflector 14 to serve as a guard for part of the knife 12 results in the exposure of a larger portion of the knife for cleaning when the deflector is removed from the machine. The deflector may be removed by means of a vertical hold 31 formed near its edge.

The slicing machine shown in Figs. VI, VII, VIII and IX is designed along less "modern" lines than that shown in Figs. I through V but similarly comprises a base 16a, knife drive housing means 11a, a rotary circular knife 12a, a gauge plate 13a and a deflector 14a which serves to deflect slices of commodity severed by the knife 12a onto a slice-receiving platter 15a. The deflector 14a is mounted on the slicing machine by means of a rod 32a which is studded into a portion of the drive housing means 11a and extends substantially horizontally rearwardly therefrom. The rod 32a is engageable in a horizontal bore 33a formed in a portion of the deflector 14a. The position of the deflector 14a, relative to the knife 12a, is determined by the engagement of an adjustably mounted pin 34a in a small hole 35a drilled through the deflector 14a. The pin 34a has an annular groove 36a cut in its shank which is engageable by a spring clip 37a riveted on the rear of the deflector 14a to hold the deflector in position with the pin 34a engaged in the hole 35a.

The pin 34a is staked into a small L shaped bracket plate 38a which is secured on a forward face 39a of the drive housing means 11a by means

of two machine screws 40a which pass through enlarged holes 41a in the bracket plate 38a and are studded into the face 39a of the drive housing means 11a.

5 By loosening the machine screws 40a and adjusting the position of the bracket plate 38a, the position of the pin 34a, and thus of the deflector 14a when the pin 34a is engaged in the hole 35a, may be adjusted with respect to the knife 12a to vary the proximity of the deflector 14a to the knife.

15 In both of the above structures there is embodied the applicant's invention, the deflector plate in each case being held on the machine by the same means which adjusts its position relative to the rear face of the rotary circular knife, and being easily and quickly removable from the machine to facilitate cleaning the knife.

20 The embodiment of the invention that has been disclosed may be modified to meet various requirements.

Having described my invention, I claim:

1. In a slicing machine having a drive housing, a rotatable circular knife, a slice receiver, and a slice deflector, mounting means for said slice deflector comprising a stud projecting from said housing substantially perpendicular to the plane of the knife, and a second stud disposed perpendicularly to said first stud and mounted in a member attached to said housing and adjustable along a line parallel to said first stud and means on said deflector plate for engaging said studs.

2. In a slicing machine having a frame, a rotary circular knife, a slice receiving platter and a deflector plate, an adjustable separable deflector plate mounting for supporting the deflector plate from the frame, said separable mounting comprising a first member that is adjustably secured to the frame of the machine and that has notches opening toward the deflector plate and extending first backward away from the plate and then continuing at right angles thereto in a direction toward the rotary knife, and second members attached to the deflector plate and having constricted shank-like portions that are engageable in the notches by movement of the deflector plate first toward the frame and then toward the knife to hold the deflector plate in fixed relation to the first member.

GEORGE R. WOOD.
